FRANKLIN S. SMITH, OF BROOKLYN, NEW YORK

CONSTRUCTION OF TRANSFORMER TANKS AND THE LIKE

Application filed August 10, 1927. Serial No. 211,983.

This invention relates to the construction of transformer tanks and the like. One of the objects thereof is to provide a construction of the above nature which is dependably fluid-tight throughout and wherein the possibility of leakage is minimized by maintaining at a minimum the number of openings employed in the tank walls. Another object is to provide means for utilizing a single opening in the tank for the insertion of a fluid dielectric or for exhausting the tank contents and for the mounting of a pressure gage. Another object is to provide a simple and practical means for forming a fluid connection with the tank interior. Another object is to provide a thoroughly dependable seal at the tank opening through which fluid is passed to or from the tank. Other objects will be in part obvious or in part pointed out hereinafter.

The invention accordingly consists in the features of construction, combinations of elements and arrangements of parts as will be exemplified in the structure to be hereinafter described and the scope of the application of which will be indicated in the following claims.

In the accompanying drawing in which is shown one of the various possible embodiments of this invention,

Figure 1 is a sectional view of a portion of a transformer tank or the like showing a pressure gage and fluid connection with the tank interior;

Figure 2 shows the parts shown in Figure 1 removed from the tank and viewed from the upper side of Figure 1;

Figure 3 is a side elevation of parts of the construction;

Figure 4 is a section of the parts shown in Figure 3 after the fluid passage has been closed, and

Figure 5 shows diagrammatically a transformer tank and means for either forcing fluid into the tank or exhausting the air therefrom.

Similar reference characters refer to similar parts throughout the several views of the drawing.

Referring now to the drawing in detail,

there is shown in Figure 1 a portion of the wall 10 of a tank which contains a high tension transformer or other electrical apparatus. In this transformer there is preferably employed a dielectric consisting of a fluid, such as a suitable gas, under high pressure. The pressure employed may be in the neighborhood of 225 pounds. It is to be understood, also, that, instead of containing a gas under high pressure, the tank may be exhausted so that the pressure therein about the transformer coils or other electrical equipment is below atmospheric and a substantial vacuum prevails. Whether the preferred high pressure gaseous dielectric or a vacuum is employed, it is of the greatest importance that there be no leakage through the tank walls. The greater the number of openings which are employed in the tank the greater becomes the difficulty of avoiding leaks and of properly sealing the tank.

Referring still to Figure 1, there is shown a member 11 threaded into an opening 13 in the tank. Mounted upon the outer end of the member 11 is a pressure gage 12 of any suitable construction, and extending through the member from the inner end thereof to the pressure gage is a fluid passage 14. Between the pressure gage and the tank walls the member 11 is provided with a somewhat enlarged and squared portion 11a which may be engaged by a wrench to thread the member 11 tightly into the opening 13.

In the part 11a of the member 11 is formed a fluid passage 15 communicating with the passage 14 at its inner end and extending outwardly therefrom toward the side of the member 11 at substantially right angles to the passage 14. The outer portion 15a of the passage 15 is enlarged and the inner end of this enlarged portion forms a valve seat 16 which is preferably substantially flat as shown. In the part 15a is a valve member which consists of a small threaded plug 17 having at its inner end a tapered surface 17a to coact with the valve seat 16. The plug 17 is provided at its outer end with a transverse slot 18 to be engaged by a screw driver for threading the valve toward and away from the valve seat 16.

When the valve member 17 is threaded inwardly against the seat 16, the fluid passage 15 is sealed thereby. The threads of the valve member 17 have preferably a somewhat loose fit with the threads of the passage portion 15a, and hence when the plug is backed away a very slight amount from the seat 16, fluid under pressure is permitted to pass through the passage 15, working its way past the threads. Preferably, also, there is formed in the side surface of the plug or valve member 17 a shallow longitudinal groove 19 which insures a free flow of fluid when the valve member is backed away from its seat. The plug 17 is of such length, preferably, that it is at all times contained wholly within the passage 15a.

In Figures 1 and 2 there is shown in position about the member 11 a rigid frame 20 which is preferably in the shape of a closed loop or rectangle. Mounted in the left-hand side of this frame, as viewed in the drawing, is a part 21 which may be termed a nozzle, having a fluid passage 22 extending axially therethrough and having at its outer or rear end means for making connection with a fluid conductor such as a flexible pipe or hose 23. The front or inner end of the nozzle 21 is provided preferably with a tapered surface 24, the end of the nozzle tapering down to a diameter less than that of the mouth of the passage 15a. Threaded in the side of the frame 20 opposite the nozzle 21, and preferably axially aligned with the nozzle, is a rod or spindle 25 having a hand wheel 26 by means of which it may be turned and advanced through the frame toward the end of the nozzle 21 or moved in the opposite direction.

The frame 20 is of such size that it is conveniently slipped into or out of position over the pressure gage 12. When the tank is being filled with a fluid under pressure, or being exhausted, the frame 20 and the parts carried thereby are placed as shown in Figures 1 and 2. The end of the nozzle 21 is registered with the passage 15a and thereupon the spindle 25 is advanced by means of the hand wheel 26 against the side of the member 11 opposite to the passage 15a. Preferably, there is formed in the surface of the member 11, against which the rounded end of the spindle 25 engages, a rounded recess 11b which properly positions the end of the spindle in line with the nozzle and the passage 15a. The parts having been thus positioned, when the spindle 25 is turned tightly up against the member 11, the end of the nozzle 21 is pulled tightly against the portion of the member 11 about the mouth of the passage 15a. The member 11 is preferably formed of brass and the nozzle 21 is preferably of steel; the tapered surface 24 of the nozzle jams tightly against the sharp edge about the mouth of the passage 15a and forms a dependable fluid-

tight connection between the fluid conductor 23 and the passage 15. The nozzle is preferably provided with a shoulder 27 which bears against the inner side of the frame 20 and takes the thrust exerted by the action of the screw 25. The rounded end of the screw or spindle 25 and the coacting rounded recess in which it operates permits the frame to rock and adjust itself as the screw is tightened so that the most effective seal is achieved at the end of the nozzle.

Prior to the adjustment of the nozzle and its clamping device into position as above described, the plug or valve member 17 is backed away a slight distance from its seat 16. The fluid conductor 23 is now connected to a source of fluid under pressure if it is desired to fill the tank, or to a vacuum pump if it is desired to exhaust the tank. As the process of filling or exhausting proceeds, the pressure gage 12 continually indicates the pressure within the tank. When the desired pressure has been achieved, the screw 25 is loosened, the clamping device is removed and the plug 17 is quickly given a slight turn to advance it against its seat 16.

It will be noted that the plug 17 is of such length that its outer end is positioned some distance from the mouth of the passage 15a and a space is left between the outer end of the plug and the end of the nozzle. The fluid passes through either by working its way through the loosely fitting threads or through the groove 19 as has been described in the foregoing. It will be seen that, after the process of filling or exhausting has been completed, the plug 17 may be very quickly seated to seal the passage without any substantial loss of pressure or vacuum.

In Figure 5 there is diagrammatically illustrated the transformer tank 10 with the apparatus hereinbefore described mounted thereon to fill or exhaust the tank. The fluid conductor 23, connected to the nozzle 21, is shown leading to a pump 28 which may be employed to force gas into the tank under pressure or to exhaust the tank contents.

After the desired filling or exhaustion of the tank has been accomplished, and after the valve plug 17 has been seated, the passage 15a exterior of the end of the plug is preferably filled with solder, as shown at 29 in Figure 4. The plug 17 is preferably formed of brass so that it forms a dependably tight seal when seated against the brass seat 16 of the member 11, and the brass is also conducive to a tight soldered joint. In addition to the soldering over the plug 17, the member 11 is preferably soldered to the tank 10 about the opening 13, as shown at 30 in Figure 1. Thus, the possibility of leakage is dependably minimized regardless of the high pressures or high vacuum employed. The construction is extremely compact and no cumbersome apparatus is left mounted

upon the transformer tank after the process of filling or the process of exhausting the tank has been accomplished.

As many possible embodiments may be made of the above invention and as many changes might be made of the embodiment above set forth, it is to be understood that all matter hereinbefore set forth or shown in the accompanying drawing is to be interpreted as illustrative and not in a limiting sense.

I claim as my invention:

1. In a device of the class described, in combination, a member having a passage for fluid therethrough, a removable device for forming a fluid-tight connection between an outer fluid conductor and said passage comprising a part having a fluid passage therethrough and means for clamping said part tightly against said first member with the mouths of said two fluid passages in registry, and means operatively related to and housed within the passage in said member for sealing said passage and having a part for operating it to effect a sealing accessible only upon removal of said device.

2. In a device of the class described, in combination, a member having a passage for fluid therethrough, a conduit for fluid, and means for forming a fluid-tight connection between said passage and said conduit comprising a second member having a fluid passage therethrough and a device for removably clamping said members tightly together with the mouths of said passages in registry, and a valve for sealing said first passage accessible for manipulation only after detachment and removal of said second member, said valve comprising a plug threaded in said first-mentioned passage and having a seat at its inner end, said plug being of such length that it is contained wholly within said passage when backed away from its seat.

3. In a device of the class described, in combination, a member adapted to be secured in an opening in a tank and having a fluid passage therethrough terminating at its outer end in a mouth positioned at one side of said member, a supporting bracket adapted to embrace said member, a fluid nozzle carried in said bracket and adapted to coat with said mouth, and a threaded member in said bracket adapted to engage the side of said member opposite said mouth and to draw said nozzle against said mouth to form a fluid-tight connection between said nozzle and said passage, said mouth having a sharp edge and the end of said nozzle being tapered to extend thereinto.

4. In a device of the class described, in combination, a member adapted to be secured in an opening in a tank and having a fluid passage therethrough terminating at its outer end in a mouth positioned at one side of said member, said passage having a

portion thereof internally threaded, a supporting bracket adapted to embrace said member, a fluid nozzle carried in said bracket and adapted to coat with said mouth, a threaded member in said bracket adapted to engage the side of said member opposite said mouth and to draw said nozzle against said mouth to form a fluid-tight connection between said nozzle and said passage, and a valve member in said passage comprising a threaded plug in threaded engagement with the threaded portion of said passage and having a seat at its inner end and adapted when backed away from its seat to permit passage of fluid, said plug being accessible from said mouth for rotation by means of a tool when said nozzle is removed and having a part exposed toward said mouth and with which part a tool may engage for rotating said plug when said nozzle is removed.

5. In a device of the class described, in combination, a member adapted to be secured in an opening in a tank and having a fluid passage therethrough terminating at its outer end in a mouth positioned at one side of said member, a supporting bracket adapted to embrace said member, a fluid nozzle carried in said bracket and adapted to coat with said mouth, and a threaded member in said bracket adapted to engage the side of said member opposite said mouth and to draw said nozzle against said mouth to form a fluid-tight connection between said nozzle and said passage, said mouth having a sharp edge and the end of said nozzle being tapered to extend thereinto, and said member being formed of brass and said nozzle being formed of steel.

6. A device for conditioning a tank or the like as to the pressure therein, comprising in combination, a member secured into an opening in a tank and having a passage for fluid therethrough, a pressure gage connected to said passage, a removable device for forming a fluid-tight connection between an outer fluid conductor and said passage, said device including a supporting bracket shaped to pass over said pressure gage and having a fluid nozzle adapted to connect with said passage and having also a threaded member adapted to engage the side of said first-mentioned member and to draw and hold said nozzle in fluid-tight connection with said passage, and means associated with said first-mentioned member for opening or closing the passage therein.

7. A device for conditioning a tank or the like as to the pressure therein comprising, in combination, a member secured into an opening in a tank and having a passage for fluid therethrough, a pressure gage connected to said passage, a removable device for forming a fluid-tight connection between an outer fluid conductor and said passage, said device including a supporting bracket shaped

to pass over said pressure gage and having a fluid nozzle adapted to connect with said passage and having means for drawing and holding said nozzle in fluid-tight connection with said passage, and valve means housed entirely within said passage for opening or closing the latter and operable only when said device and said nozzle are removed from said member.

8. In apparatus of the class described, in combination, a tank, a stem projecting outwardly from said tank and having a passage for fluid extending therethrough, a valve in said passage, a gage permanently connected to said member and communicating with said passage in front of said valve to indicate at all times the pressure within said tank, and detachable means for forming a fluid-tight connection between an outer fluid conductor and said passage.

9. In apparatus of the class described, in combination, a tank, a stem projecting outwardly from said tank and having a passage therein leading from the interior of said tank to a port on one side of said stem, a valve seat in said passage, a plug threaded in said passage and forming a valve to coact with said seat, a gage permanently connected to said stem and communicating with said passage in front of said valve to indicate at all times the pressure within said tank, and means for clamping a fluid conductor to said stem in registration with said port, said valve being operable by a tool inserted through said port.

10. In apparatus of the class described, the combination with a tank of means for conditioning said tank as to pressure therein comprising a stem projecting outwardly from said tank and having a passage leading from the interior of the tank to a port on one side of said stem, a valve in said passage operable through said port to control the flow of fluid through said passage, a supporting frame adapted to embrace said stem, a fluid nozzle carried in said frame and adapted to coact with said port, and a member adapted to engage the side of said stem opposite said port to draw said nozzle against said port to form a fluid-tight connection between said nozzle and said passage, said valve being accessible only when said frame is removed.

11. A device for conditioning a tank or the like as to pressure therein comprising, in combination, a member threaded into an opening in a tank and having a passage communicating with the interior of said tank, a second passage leading from the first-mentioned passage and having a port on one side of said member outside said tank, a valve seat formed in said second passage, and a threaded plug in said second passage forming a valve to coact with said valve seat and operable by a tool inserted through said port.

12. A device for conditioning a tank or the like as to pressure therein comprising, in

combination, a member threaded into an opening in a tank and having a passage communicating with the interior of said tank, a second passage leading from the first-mentioned passage and having a port on one side of said member outside said tank, a valve seat formed in said second passage, a threaded plug in said second passage forming a valve to coact with said valve seat and operable by a tool inserted through said port, and a removable device for forming a fluid-tight connection between an outer fluid conductor and said second passage including a part having a fluid passage therethrough, and means for clamping said part tightly against said member with the mouth of the passage in said part registering with said port, said valve being accessible only when said device is removed.

13. A device for conditioning a tank or the like comprising, in combination, a member having its inner end threaded into an opening in a tank and a passage extending from an inner port communicating with the interior of said tank to an outer port on one side of said member outside said tank, a valve seat in said passage, a threaded plug in said passage forming a valve coacting with said seat and operable only by a tool inserted through said outer port, a supporting frame adapted to envelope said member, a fluid nozzle carried by said frame, and a clamping screw in said frame adapted to engage the side of said member opposite said outer port to draw said nozzle against said outer port to form a fluid-tight connection between said nozzle and said passage, said valve being accessible only when said frame is removed.

In testimony whereof, I have signed my name to this specification this twenty seventh day of July, 1927.

FRANKLIN S. SMITH.
